UNITED STATES PATENT OFFICE

MARTIN M. CLAYTON, OF BADEN, PENNSYLVANIA, ASSIGNEE, BY MESNE ASSIGNMENTS,
TO NATIONAL ELECTRIC PRODUCTS CORPORATION, A CORPORATION OF DELAWARE

ELECTRICAL SOCKET

Application filed April 14, 1928. Serial No. 270,013.

The invention has to do with sockets for electric lamps, etc., of the well known type, which are usually made of porcelain or other non-conducting substances, molded to form 5 while in a plastic state and then baked into a hard body. Such sockets are usually mounted upon the face of a supporting plate having an opening which receives the rear end portion of the socket, and the body of the 10 socket is provided with integral ears or lugs which bear against the outer face of the supporting plate, to which they are secured by means of screws passed through the lugs and the plate. Considerable losses are incurred 15 by breakage of these lugs in shipment and handling of the sockets, as well as in screwing them into place upon their supports. It is the object of the present invention to provide a socket of a form less susceptible to 20 breakage, which requires less porcelain, is less expensive to manufacture, may be easily secured in place, and is of neat and attractive appearance.

In the accompanying drawings Figure 1 25 is a view in elevation of the socket secured to its support, a portion of its rear edge being shown as broken away, and Figure 2 is a rear end view.

The supporting plate 1 may be the cover of 30 an outlet-box, or other member of a wiring system, or any suitable support, provided with an opening 2, through which the barrel or body-portion 3 of the socket is projected from the rear until the projecting rear flange 35 or shoulder 4 of the socket bears against the rear wall of the plate around the opening 2, in which position the socket is secured to its supporting plate by any suitable means. For 40 securing the socket to the plate I prefer to use the lugs 5, each having the oppositely bent fingers or ears 6 and 7, the ear 6 being bent inwardly to bear upon the rear face of the shoulder 4 of the socket, and the ear 7 being bent outwardly adjacent to the rear 45 face of the plate 1, to which it is secured by a screw 8 which passes through a hole in the plate and works in a threaded hole in the ear 7. In order to prevent turning of the socket 50 it is preferred to form seats 9 for the fingers or ears 6 in the rear face of the shoulder 4.

If these seats 9 are made slightly wider than the ears 6, there will be obtained a slight freedom of movement which will tend to prevent breakage of the socket in case of a blow against its supporting plate. 55

It will be noted that the fingers or ears 6 of the clamps 5 are shown as being relatively narrow with respect to the periphery of the shoulders 4 of the socket, so that the width of the bearing surface of each finger upon the 60 rear face of the shoulder is small, and, as last above stated, less than the width of the seats 9 when the latter are present. There is thus provided a capacity of a slight swiveling movement of the socket under stresses or jars, 65 and consequent avoidance of breakage.

I claim as my invention:

1. The combination with a support having an orifice, of an electrical socket projected through said orifice from the rear, an integral peripheral shoulder on said socket bearing against the rear face of the support, seats formed in said shoulder, clamps seated in the 70 seats, and means for securing the clamps to the support. 75

2. The combination with a support having an orifice, of an electrical socket projected through said orifice from the rear, an integral peripheral shoulder on said socket bearing against the rear face of the support, a plurality of clamps, seats for the clamps formed in the shoulder of width sufficient to permit limited lateral movement of the clamps therein, and means for securing the 80 clamps to the support. 85

3. The combination with a support having an orifice, of an electrical socket projected through said orifice from the rear, an integral peripheral shoulder on said socket bearing against the rear face of the support, and a pair of oppositely disposed clamps each having a relatively narrow finger bearing upon the rear face of said shoulder, and means securing said clamps to said support. 90

In testimony whereof I have hereunto set 95 my hand.

MARTIN M. CLAYTON.
